UNITED STATES PATENT OFFICE

124,426

DESIGN FOR A DESK OR THE LIKE

Ernest O. Carlson, Rockford, Ill.

Application April 1, 1940, Serial No. 91,401

Term of patent 14 years

To all whom it may concern:

Be it known that I, Ernest O. Carlson, a citizen of the United States, residing at Rockford, in the county of Winnebago and State of Illinois, have invented a new, original, and ornamental Design for a Desk or the like, of which the following is a specification, reference being had to the accompanying drawing, forming part thereof.

In the drawing:

Fig. 2 is a front perspective view showing the parts in moved position.

The opposite end of the desk or the like is substantially the same as that shown and the back of the desk or the like is plain.

The dominant features of my design reside in the portion shown in solid lines.

I claim:

The ornamental design for a desk or the like, substantially as shown and described.

ERNEST O. CARLSON.
